CLOSURE FASTENER

Application filed December 16, 1927. Serial No. 240,372.

Our invention relates generally to the type of flexible closure fasteners of the continuous type, such as described, for instance, in U. S. Letters Patent No. 1,219,881.

5 The present invention relates more particularly to novel means for effecting the opening and closing of the fastener or what may be termed generally as the operating slide. Thus, our invention relates particularly to a 10 novel operating slide and handle member therefor which possess certain novel structural as well as functional features, resulting particularly in greater ease of operation in the opening and closing of the fastener and 15 permitting the concealment of the handle in relatively thin spaces, and also providing means for locking the operating slide in any desired position along the flexible closure fastener.

20 For the purpose of illustrating our invention we have shown in the accompanying drawings forms thereof which are at present preferred by us, since the same have been found in practice to give satisfactory and 25 reliable results, although it is to be understood that the various instrumentalities of which our invention consists can be variously arranged and organized and that our invention is not limited to the precise arrangement 30 and organization of the instrumentalities as herein shown and described.

In the accompanying drawings:

Fig. 1, represents a front elevation, on a greatly enlarged scale, of a flexible closure fastener having the operating slide and handle of our novel construction applied thereto.

Fig. 2, represents a section generally on line 2-2 of Fig. 1, illustrating our novel pivotal handle construction and locking means carried thereby; shown in the locked position.

Fig. 3, represents a section similar to that shown in Fig. 2, illustrating the handle in the unlocked position, to wit, turned at an angle of 90° to the locked position shown in Figure 2.

Fig. 4, represents a view in elevation, detached, of one of the pair of opposed cam plates of the operating slide of our novel construction.

50 Fig. 5, represents a front elevation of a

swivelled handle member of a slightly modified construction.

Fig. 6, represents a section on line 6-6 of Fig. 5.

Fig. 7, represents a front elevation of a 55 handle of a further modified construction.

Fig. 8, represents an elevation of a swivelled handle having locking means therein of a modified construction.

Fig. 9, represents a section on line 9-9 of 60 Fig. 8.

The operating slide of our novel construction is designated generally by the numeral 10 and comprises a pair of two opposed cam plates 11 and 12, fixedly connected to each other and maintained in rigid and fixed spaced relation to each other by an intermediate spacing and supporting member 13. Each of the two opposed cam plates 11 and 12 is provided with opposed and spaced camming flanges 14 and 15 diverging at both ends so as to present not only suitably inclined entering cams or channels 16 but so as also to form slightly inclined, outwardly diverging, 70 receding cams 17.

The outer cam plate 11 is provided with a laterally and generally horizontally projected handle socket member 18 having therein a generally horizontal, cylindrical bearing opening 19. A handle member 20 of any 80 suitable shape and size is provided with a trunnion portion 21, either rigidly affixed thereto or formed integrally therewith. The trunnion portion 21 is journalled in the bearing opening 19 thereby maintaining the 85 handle member 20 in swivelled relation to the operating slide 10. In order to lock the trunnion portion 21 and handle member 20 in the socket 18 of the operating slide 10, against axial displacement of the handle member 90 with respect to the operation slide, that is against removal from the socket, the trunnion portion 21 is preferably provided with somewhat enlarged diameter flanges 22 and 23, with a smaller diameter groove 24 intermediate thereof. The outer end of the socket 18 is provided with a correspondingly enlarged bore as at 25, having a relatively thin wall. In assembling the slide 10 and swivelled handle member 20, the trunnion portion 95

100

21 is mounted in the socket 18, and the relatively thin wall of the outer portion of the socket 18 is rolled or indented into the annular channel 24 of the trunnion portion 21, as at 26, forming an annular bead therein and establishing a permanent swivelling connection or engagement between the socket 18 and trunnion portion 21, against any axial displacement relative to each other.

10 Due to the swivelled connection between handle member and slide, about a fixed horizontal axis, the slide 10 may be operated with greater facility under conditions which render the slide more or less inaccessible. Thus, 15 for instance, the pivotal handle member and slide of our present novel construction is particularly adapted for use with closure fasteners of the character stated, in garment constructions such as disclosed in Patents 20 Nos. 1,665,855 and 1,665,856 issued to us, where it is desirable and preferable to operate the slide from one side, or off-center. The slide of the novel construction is further particularly adapted for garment constructions 25 of this character because the operating handle member, by virtue of its swivelled mounting, is capable of being turned so as to lie flush with the relatively thin operating slide and thereby reduce to a minimum, the aggregate 30 thickness of the closure fastener. Thus, when it is desired to operate the slide 10, the relatively flat handle portion is turned at a right angle to the direction of movement of the slide, as shown in Fig. 3, and also by the 35 dotted lines in Fig. 1, so that a substantial grip may be had on the handle portion. When the slide is not in actual operation the handle portion is turned at a right angle, into the position shown in solid lines in Fig. 1, in 40 which case it is flush with, and occupies substantially the same plane as, the slide 10.

In order to lock the slide 10 at any desired position along the continuous, flexible fasteners of the conventional construction, designated generally by the numerals 27 and 28, the innermost end of the trunnion portion 21 of the handle member 20 is provided with a flat, terminal locking member or detent 29, carried rigidly by the trunnion portion 21 50 and positioned preferably at a right angle to the plane of the handle portion, as shown in Figs. 2 and 3. When the flat locking member or detent 29 is turned parallel to the row of fasteners 27, as indicated in Fig. 3, it 55 clears the edges of said fasteners and thus permits the operating slide 10 to be moved freely in either direction for opening or closing, respectively. When, however, the handle portion is turned parallel or flush with the 60 slide 10, into the position shown in solid lines in Fig. 1 and as indicated in Fig. 2, the flat detent 29 is positioned transversely of the row of fasteners 27, with an edge thereof disposed between two adjacent fastener members, thereby interlocking the slide 10 with

the row of fasteners 27 and thus preventing any movement of the slide 10.

This is of particular advantage as it will prevent the accidental opening or closing of the fastener, particularly the former. Thus, 70 in order to move the slide 10, so as to unlock or open the fastener, it is necessary first to turn the handle portion into a position substantially at a right angle to the direction of movement of the slide or at a right angle to the line of fasteners 27; thereby to unlock 75 the slide.

In Figures 8 and 9 we have illustrated a handle portion 30 of a modified construction, having a central aperture 31 therethrough, in 80 which the female part 32 of a snap fastener may be permanently affixed in a manner shown particularly in Figure 9. By this means the handle 30 may be locked in any 85 position by means of a male snap fastener part 33 sewed to the cloth 34 as indicated in dotted lines in Figure 9.

In Figures 5 and 6 we have illustrated a still further modified handle construction in 90 which the stem or trunnion portion 21 is bifurcated at its outer end as at 35 and a non-metallic disk of suitable shape, such as a bone or ivory disk 36 is inserted into the bifurcated end 35 and secured thereto by means of a rivet 37 as well as by other suitable gripping means such as the inwardly projecting edge portions or claws 38.

In Figure 7 we have illustrated a still further modified handle construction in which a continuous annular, thin metallic frame 100 39 is formed integrally with the stem or trunnion portion 21 and any suitable non-metallic disk 40 is inserted and affixed permanently in the thin metallic frame 39, thereby to form a composite handle member.

105 It is a characteristic feature of the invention that the handle member is off-center or to one side of the slide in an operating condition. The sides of the slide should be understood herein to mean the left and right hand side of the slide as viewed in Figure 1 of the drawing. Thus, it is also a characteristic feature of this invention that the handle member is off-center with respect to the slide. The center line herein referred to is 110 the center line passing between the two rows of fasteners, 27 and 28. Likewise, the term "trunnion" used herein should be construed in the more specific sense, to wit; an elongated supporting member journaled at one 115 end in a bearing and overhanging at the other end in a cantilever fashion.

120 It will thus be seen that by our novel construction in an operating slide and handle member for closure fasteners, not only is the 125 opening and closing of the fastener greatly facilitated in concealed places not easily accessible, but by means of our novel construction an operating slide and handle is provided which is particularly adapted for use 130

in garments because it is relatively thin and is thus of particular advantage also in the pressing or ironing of the garment. Operating slides and handles of closure fasteners of this character have heretofore been quite bulky or thick and have consequently greatly interfered with the proper pressing of garments within which they were contained.

We are aware that our invention may be embodied in other specific forms without departing from the spirit or essential attributes thereof, and we therefore desire the present embodiments thereof to be considered in all respects as illustrative and not restrictive, reference being had to the appended claims rather than to the foregoing description to indicate the scope of the invention.

Having thus described our invention what we claim as new and desire to secure by Letters Patent, is:—

1. An operating slide for flexible closure fasteners having diverging fastener-receiving guide channels, having a bearing socket therein with its axis disposed transversely of the direction of travel of the slide, a handle having a rigid trunnion portion having one end thereof swivelled in said socket; said handle being permanently disposed to one side of the operating slide.

2. An operating slide for flexible closure fasteners having diverging fastener-receiving guide channels, having a bearing socket therein, a handle trunnion swivelled in said bearing socket and means carried at one end of said trunnion for locking the slide in any desired position along the fastener.

3. In an operating slide for flexible closure fasteners having diverging fastener-receiving guide channels, a bearing socket in one side of the slide having its axis extending transversely of the direction of travel of the slide and substantially parallel to the plane of the fasteners, and a handle member disposed to one side of the slide in the operative position thereof, said handle member including a trunnion stem having one end thereof journalled in said bearing socket.

4. In an operating slide for flexible closure fasteners of the character stated, a cam plate, having a bearing socket therein with its axis disposed transversely of the direction of travel of the slide, a trunnion portion having one end thereof journalled in said socket and means carried by the journalled end of the trunnion portion for interengaging with the row of fasteners of the flexible closure fastener, thereby to lock the operating slide with respect to said flexible closure fastener.

5. In an operating slide for flexible closure fasteners of the character stated, a cam plate, having a bearing socket therein with its axis disposed transversely of the direction of travel of the slide, a trunnion portion having one end thereof journalled in said socket, a handle portion carried by the outer end of

said trunnion portion, and means carried by the journalled end of the trunnion portion for interengaging with a row of fasteners of the flexible closure fastener when the handle portion and trunnion portion are revolved, thereby to lock the operating slide with respect to said flexible closure fastener.

6. In an operating slide for flexible closure fasteners of the character stated, a bearing socket in one side of the slide having its axis extending transversely of the direction of travel of the slide and substantially parallel to the plane of the fasteners, a trunnion portion having one end thereof journalled in said socket, a handle portion carried by the outer end of said trunnion portion and a detent carried by the journalled end of the trunnion portion for inter-engaging with the row of fasteners of the flexible closure fastener, thereby to lock the operating slide with respect to said flexible closure fastener.

7. In an operating slide for flexible closure fasteners of the character stated, a bearing socket in one side of the slide having its axis extending transversely of the direction of travel of the slide and substantially parallel to the plane of the fasteners, a trunnion portion having one end thereof journalled in said socket, a handle portion carried by the outer end of said trunnion portion and means carried by the journalled end of the trunnion portion for inter-engaging with a row of fasteners of the flexible closure fastener when the handle portion and trunnion portion are revolved, thereby to lock the operating slide with respect to said flexible closure fastener.

8. In an operating slide for flexible closure fasteners having a bearing socket at a side thereof with its axis disposed transversely of the direction of travel of said slide, an operating handle having a rigid trunnion stem journalled in said bearing socket, and means carried by the trunnion stem for inter-engaging with the row of fasteners of the flexible closure fastener, thereby to lock the operating slide with respect to said flexible closure fastener.

9. In an operating slide for flexible closure fasteners having a bearing socket at a side thereof with its axis disposed transversely of the direction of travel of said slide, an operating handle having a rigid trunnion stem journalled in said bearing socket, and means carried by the trunnion stem for inter-engaging with a row of fasteners of the flexible closure fastener when the handle member and trunnion stem are revolved, thereby to lock the operating slide with respect to said flexible closure fastener.

10. In an operating slide for flexible closure fasteners of the character stated, a bearing socket in said slide, and a handle member including a trunnion portion having one end thereof swivelled in said bearing socket and having the other end thereof extending be-

yond the same and a handle portion rigidly carried on the free end of said trunnion portion.

11. In an operating slide for flexible closure fasteners of the character stated, a bearing socket in said slide extending transversely of the direction of travel of said slide, a trunnion portion having one end thereof swivelled in said bearing socket and having the other end thereof extending beyond the same, and a handle portion rigidly carried on the free end of said trunnion portion.

12. In an operating slide for flexible closure fasteners of the character stated, a bearing socket in said slide, a handle member including a trunnion portion having one end thereof journalled in said bearing socket and having the other end thereof extending beyond the same, a handle portion carried rigidly on the free end of said trunnion portion, and means to retain said trunnion portion against axial displacement.

13. In an operating slide for flexible closure fasteners of the character stated, a bearing socket in said slide extending transversely of the direction of travel of said slide, a trunnion portion having one end thereof journalled in said bearing socket and having the other end thereof extending beyond the same, a handle portion rigidly carried on the free end of said trunnion portion, and means to retain said trunnion portion against axial displacement.

14. An operating slide for flexible closure fasteners having diverging fastener-receiving guide channels, including a handle carried by and permanently projecting to one side of the slide, in an operative condition.

15. An operating slide for flexible closure fasteners having diverging fastener-receiving guide channels, including a handle member swivelled to the slide and extending permanently in a direction transversely of the direction of travel of said slide.

16. An operating slide for flexible closure fasteners having diverging fastener-receiving guide channels, including a handle carried by and extending permanently to one side of the slide in a direction transversely of the path of travel of said slide and in an operative condition.

17. An operating slide for flexible closure fasteners having diverging fastener-receiving guide channels, including a handle member swivelled to the slide and extending permanently to one side of the slide in a direction transversely of the path of travel of the slide.

18. An operating slide for flexible closure fasteners having diverging fastener-receiving guide channels, including an off-center handle with respect to and carried by the slide, projecting permanently to one side of the slide, and means for locking the slide in any desired position.

19. An operating slide for flexible closure

fasteners having diverging fastener-receiving guide channels, including a swivelled, off-center handle with respect to and carried by the slide, projecting permanently to one side of the slide, and means carried by the handle for locking the slide in any desired position.

20. An operating slide for flexible closure fasteners having diverging fastener-receiving guide channels, including a handle member swivelled to the slide and extending permanently in a direction transversely of the direction of travel of the slide, and means carried by the handle member for locking the slide in any desired position.

21. An operating slide for flexible closure fasteners having diverging fastener-receiving guide channels, including a handle carried by and extending permanently to one side of the slide in a direction transversely of the path of travel of the slide, and means carried by the handle for locking the slide in any desired position.

22. An operating slide for flexible closure fasteners having diverging fastener-receiving guide channels, including a handle member swivelled to the slide and extending permanently to one side of the slide in a direction transversely of the path of travel of the slide, and means carried by the handle member for locking the slide in any desired position.

23. The combination with a flexible closure fastener of the character stated, of an operating slide having diverging fastener-receiving guide channels, including a handle member carried by and extending transversely of the direction of travel of said slide upon said flexible closure fastener, and off-center with respect to said closure fastener operating slide, in an operative condition thereof.

24. The combination with a flexible closure fastener of the character stated, of an operating slide therefor having diverging, fastener-receiving guide channels, including a handle member carried by and projecting transversely of the direction of travel of said slide upon said fastener, and being to one side of said fastener in the operative condition thereof.

In witness whereof we have hereunto set our hands.

ARTHUR S. LICHTEN.
